United States Patent

Des. 236,489
Patented Aug. 26, 1975

236,489

CARD READER OR THE LIKE

Charles A. Pycha and Frank Wilkey, Jr., Rochester,
Minn., assignors to International Business Machines
Corporation, Armonk, N.Y.

Filed Apr. 8, 1974, Ser. No. 459,247

Term of patent 14 years

Int. Cl. D14—02

U.S. Cl. D26—5 C

FIG. 1

FIG. 1 is a left front perspective view of a card reader showing our new design; and

FIG. 2 is a right rear perspective view thereof.

The stack of cards shown in broken lines in FIG. 1 is for illustrative purposes only and forms no part of the claimed design.

We claim:

The ornamental design for a card reader or the like, as shown and described.
